UNITED STATES PATENT OFFICE

2,685,341

IMPELLER OR PROPELLER HAVING
ADJUSTABLE BLADES

Jan C. Busquet, Hengelo, Netherlands, assignor to
Koninklijke Machinefabriek Gebr. Stork & Co.
N. V., Hengelo, Netherlands, a company of the
Netherlands

Application January 11, 1951, Serial No. 205,587

Claims priority, application Netherlands
January 16, 1950

5 Claims. (Cl. 170—160.34)

1

My present invention relates to devices for adjusting the vanes of an impeller for a fan, a pump, a water turbine or the like, or of the blades of a ship's propeller or an aircraft propeller, in which during operation the driving gear of the adjusting device is disconnected from the control mechanism.

In adjusting devices of this character the impeller or the propeller is stopped before adjusting the blades, since otherwise the driving gear of the adjusting device would be liable to damage. With a view thereto a brake is provided for reducing the coasting or deceleration time of the impeller or the propeller after the cutting out of the driving motor and for preventing the impeller or the propeller, during said adjustment of the blades, from undue rotation under the influence of forces acting thereon. Also during coasting of the impeller or the propeller the throwing in of the adjusting device may give rise to difficulties.

The object of my present invention is to obviate said drawback. With this object in view, the invention consists herein that the operating member, whereby the control mechanism is connected to or disconnected from the driving gear of the adjusting device, is associated with a movable element cooperating with a part, which is compelled to follow rotation of the impeller shaft or of the propeller shaft and adapted, during rotation of said shaft, to prevent the control mechanism from being connected to the driving gear of the adjusting device.

In order that my invention may be more fully understood, I shall now proceed to describe two embodiments thereof with reference to Figs. 1, 2 and 3, and Figs. 4 and 4a, respectively, of the annexed drawing, wherein:

Fig. 1 is a longitudinal sectional view, partly in elevation, of a fan having adjustable blades and provided with a device in accordance with the invention,

Fig. 2 is a longitudinal sectional view, drawn on an enlarged scale, of the driving gear of the adjustable blades, and

Fig. 3 is a cross-sectional view along the line III—III in Fig. 1, also drawn on an enlarged scale.

Fig. 4 is a side elevation, partly in section, of

2

an adjusting device in accordance with the invention, and

Fig. 4a shows in rear elevation a detail of said device.

5 In accordance with Figs. 1, 2 and 3, the stems 2 of the blades 1 are rotatably mounted in the hub 4 of the impeller, which hub is secured to the shaft 3 of the fan. Also secured to said shaft is the hub member 5, and slidably mounted on, 10 but locked against rotation relative to said hub member is the adjusting disk 6. Each blade is associated with the disk 6 through an arm 7, one end of which engages the stem of the blade, the other end being hinged to disk 6. Threaded in disk 6 are a plurality of, for instance three self-braking screw spindles 8, which are rotatably mounted in the hub member 5 but prevented from axial movement relative thereto. Secured to each of said spindles is a spur pinion 9. All 15 pinions 9 mesh with a spur wheel integral with the bevel gear 10, which is loosely mounted on the shaft 3 and adapted to cooperate with the bevel pinion 13. Secured to the shaft 3, on the left hand side of the gear 10 in Fig. 2, is a ratchet 20 wheel 11 adapted to cooperate with a ratchet 12 (see Fig. 3) pivoted to the inner end of a rod 14 and loaded by a spring 15.

25 It is to be noted that the ratchet wheel 11 is the "part" and that the ratchet 12 is the "movable element" referred to in the third paragraph of this specification.

In order that the bevel gears 10 and 13 may be moved into mesh so as to effect adjustment of the blades 1, the operating member constituted 30 as a hand wheel 16 (Fig. 3) is secured to screw spindle 17, which is locked against lengthwise movement and cooperates with a nut 18 having diametrically opposed stud pins engaged by slots in one end of the bifurcated lever 19, the other 35 end of which is pivoted to the collar 21 on the shaft 20 of the pinion 13. Intermediate its ends, the lever 19 is pivoted to a link, which itself is pivoted to the rod 14. Shaft 20 is loaded by the coiled spring 25 bearing against the collar 21 and 40 to a frame part. In this connection it is to be remarked, that the mechanism described in this paragraph is the "control mechanism" referred to in the third paragraph of this specification.

45 Assuming the impeller to rotate, irrespective of whether its speed is high or low, then, if the

50

handwheel 16 is turned in the proper direction with a view to bringing the bevel gears 10, 13 into mesh, the nut 18 will move outwards, i. e. towards the wheel 16, but the lever 19 will swing about the trunnions of the collar 21 in outward position, so that the rod 14 and the ratchet 12 pivoted thereto are also moved outwards. Owing thereto, the tail of the ratchet 12 rides downhill on the cam face 22 under the influence of the spring 15, which urges the ratchet towards the ratchet wheel 11. However, since this ratchet wheel rotates in the direction indicated by the arrow in Fig. 3, the ratchet 12 will not be caught in said wheel but idly slide thereon, until the nut 18 abuts against the collar 23 on the spindle 17 so as to prevent handwheel 16 from further rotation.

Consequently, the shaft 20 cannot be raised and the bevel pinion 13 cannot be brought into mesh with the bevel gear 10.

If, however, the fan stands idle, outward movement of the nut 18 by rotation of the handwheel 16 will cause the ratchet 12 to immediately catch in the ratchet wheel 11, which, under these conditions, will also be stationary, so that the pivot 24 cannot descend and the lever 19, owing to its swinging movement about the said pivot, will raise the collar 21 and the shaft 20 against the thrust of the coiled spring 25, whereby the bevel pinion 13 is brought into mesh with the bevel gear 10. During this upward movement of shaft 20, a dog 27 on this shaft engages a notch in the hub of the handwheel 26, so that rotation of this handwheel will be transmitted, through the selfbraking threaded connection between the screws 8 and the disk 6, to the blades 1, which are thereby angularly adjusted. This adjustment can be read on an indicator 28, which is associated with the shaft 20.

When the blades 1 have been properly adjusted, the handwheel 16 is to be turned in a direction whereby the nut on the spindle 17 is again moved inwards and the lever 19 is again swung about the stationary pivot 24, thereby causing, in cooperation with spring 25, the shaft 20 to be moved away from the shaft 3 and, consequently, the pinion 13 to disengage the gear 10. Simultaneously, the rod 14 is shifted towards the shaft 3, whereby the tail of the ratchet 12 again rides uphill on the cam face 15 and the ratchet is caused to clear the ratchet wheel 11.

To prevent the fan from starting during the adjustment of the blades 1, the lever 19 is adapted to operate an auxiliary switch (not shown), thereby locking the main switch of the motor, which is provided for driving the fan, as long as the bevel wheels 10 and 13 are in mesh. Should this electric safety device fail to properly function, the ratchet 12 will become inoperative as soon as the shaft 3 with the ratchet wheel 11 keyed thereon are rotated, so that the ratchet, together with the rod 14, is moved outward under the thrust of the spring 25, whereby the shaft 20 is also moved outwards and the pinion 13 is disconnected from the wheel 10. It will thus be understood that damage of the driving gear owing to undue starting of the fan is positively avoided.

Turning now to Figs. 4 and 4a, it will be seen that a disk 29 having a circumferential V-groove is secured to the housing forming part of the hub of the fan. The rod 14 here is not provided with a ratchet, as in the embodiment described with reference to Figs. 1-3, but with a tumbler 30 pivoted thereto and fitting the V-groove in

disk 29, spring blades being provided on either side of the tumbler to normally hold the latter in alignment with the rod 14. The handwheel 16 for bringing the bevel wheels 10, 13 into mesh is adapted to rotate the screw spindle 17 through the medium of a chain drive, so that rotation of said handwheel causes the nut 18 to move inwards along said spindle and thereby the lever 19 to swing about the collar 21. Owing to this swinging movement of the lever 19, the rod 14 is moved towards the shaft 3.

If, now, the fan should still be in operation, the tumbler 30 will swing about its pivot as soon as it is engaged by the walls of the V-groove in the disk 29, so that the rod 14 has freedom of further movement towards the shaft 3, until the nut 18 abuts against the enlarged inner end of the screw spindle 17. This prevents any further rotation of the handwheel 16, so that it is impossible for the bevel wheels 10 and 13 to be brought into mesh.

If, however, the fan stands idle, the tumbler 30 will not swing about its pivot when engaging the disk 29, so that it prevents the rod 14 from further movement towards the shaft 3. Owing thereto, the lever 19 during its swinging movement will urge the shaft 20 inward against the thrust of the spring 25, so that the pinion 13 will mesh with the wheel 10 and the dog 27 of said shaft will be engaged by the notch in the hub of the handwheel 26, the consequence being that further rotation of this handwheel will cause adjustment of the blades 1. The return movement of the shaft 20, i. e. the disconnection of the wheels 10, 13, is brought about by rotation of the handwheel 16 in opposite direction.

On failure of the electric safety device to operate to prevent starting of the fan as long as the blades are being adjusted, the slightest rotary movement of the fan will cause tumbler 30 to swing out of neutral position, whereupon the spring 25 is adapted to force the pinion 13 out of mesh with the bevel wheel 10.

What I claim is:

1. An impeller or propeller comprising a rotatable member, a plurality of blades pivotally mounted on said rotatable member, means rotatable with and connected to said blades for adjusting said blades about their pivotal mountings, said means including a drive pinion that is rotatable relative to said blades to operate said means and a disc that is in fixed relation with said blades, a movable pinion for engaging said driving pinion to adjust said blades, an operating member, a lever coupled to said operating member and to said movable pinion, a slid able rod connected to said lever, and a lock element pivotally mounted on the end of said rod and cooperative with said disc only when said disc is stationary to provide a fulcrum for said lever and cause meshing movement of said pinion upon operation of said member, said lock element being pivotal upon rotatable movement of said disc to release said rod and permit said lever to float and thereby prevent meshing of said pinions during rotation of said blades.

2. A device as defined in claim 1 comprising spring means between said movable pinion and its support and biasing said movable pinion from engagement with said drive pinion.

3. A device as defined in claim 1 wherein said disc comprises a ratchet wheel and said lock element comprises a pawl.

4. A device as defined in claim 1, wherein said disc has a V-groove in its periphery, and said

lock element comprises a tumbler engageable in said groove.

5. A device as defined in claim 1 wherein said means comprises a crank on each blade, a second disc axially movable relative to said blades, links between said second disc and said blade cranks, said disc having at least one internally threaded bore, a rotatable screw axially fixed relative to said blades and threaded in said bore, a pinion fixed on said screw, and a second pinion in mesh with said screw pinion and fixed with said drive pinion.
